UNITED STATES PATENT OFFICE.

LOUIS FRIEDMANN AND HANS DEUTSCH, OF VIENNA, AUSTRIA.

STEAM INJECTOR OPERATING WITH LIVE STEAM AND EXHAUST STEAM.

Application filed December 5, 1924. Serial No. 754,195.

To all whom it may concern:

Be it known that we, LOUIS FRIEDMANN and HANS DEUTSCH, both citizens of Austria, and residents of Vienna, Austria, have 5 invented certain new and useful Improvements in Steam Injectors Operating With Live Steam and Exhaust Steam, of which the following is a specification.

It is well known that with locomotive engines operating at the customary boiler pressures, the injection of feed water by the pressure of exhaust steam alone is not possible and can be accomplished only by using some live steam in conjunction with 10 the exhaust steam. Our present invention relates to an injector which can be readily changed from operation with live steam alone to operation with a mixture of live steam and exhaust, and vice versa, the construction being simple and reliable.

Several satisfactory embodiments of our present invention are illustrated by the accompanying drawings in which Fig. 1 is a longitudinal vertical section showing a 15 type of injector in which the change from one mode of operation to the other is effected by a manually operated valve; Fig. 2 is a partial vertical section showing another form of the invention, likewise with a manually operated valve; Fig. 3 is a view similar to Fig. 1 but showing an arrangement with an automatic valve for changing from one mode of operation to the other; Fig. 4 is a detail view showing a construction similar 20 to that of Fig. 3, with the addition of a manually controlled valve for the admission of live steam; and Figs. 5 and 6 are longitudinal sections corresponding substantially to Figs. 1 and 3 and showing two further 25 constructions.

In Fig. 1 we have indicated the live steam nozzle at 1 while 2 designates the exhaust nozzle into which the live steam nozzle projects, and 3, an annular chamber surrounding 30 the live steam nozzle and adapted to discharge steam into the exhaust nozzle 2. The exhaust steam enters at 4 and, under certain conditions explained hereinafter, passes through the channel or chamber 5 to the nozzle 2. Water is admitted at 6 and passes 35 out at 7 under normal conditions, while any excess of water is expelled through the valved outlet 8. Live steam is conveyed to the nozzle 1 through a pipe or conduit 9 and also to the chamber 3 through a conduit 10, preferably having a constricted por-

tion, so that the steam may have its pressure reduced materially before it passes into the chamber 5 or into the nozzle 2. Under certain conditions live steam will also pass 40 through a conduit 11 to a chamber 12 containing a suitable valve 13 of any appropriate construction, adapted to be lifted by the pressure of the steam flowing from the conduit 11 to the chamber 12. This valve 45 when lifted is adapted to engage and unseat another valve 14 which controls the communication between the chamber 5 and the inlet 4 for exhaust steam. At 15 we have shown a double piston valve adapted to be 50 shifted in either direction by means of a manually operated lever 16. In the end position shown in Fig. 1, this valve allows the live steam entering at 17 to pass to the two conduits 9 and 10 and therefore to the 55 nozzle 1 and to the chamber 3 respectively. It will be understood that from the chamber 3 steam is discharged in an annular jet surrounding the nozzle 1, into the nozzle 2. Should the valve 15 be moved to the other 60 end position, it will admit live steam into the conduit 11 which was previously disconnected from the steam supply and at the same time into the conduit 9 supplying 65 steam to the inner nozzle 1, while the supply of steam will be shut off from the conduit 10. The position of the valve 15 shown in Fig. 1 is employed when the injector is 70 to be operated by live steam alone, which is the case for instance when the engine is 75 standing still or coasting. In this case the live steam will enter the conduits 9 and 10 and the injector will be operated by the live steam issuing from the nozzle 1 and also by 80 the expanded steam passing from the chamber 3 into the exhaust nozzle 2. Since steam 85 is shut off from the conduit 11 and the chamber 12, there is no pressure in this conduit and chamber, and the valves 13 and 14 will therefore rest on the seats below them, thus 90 closing the communication from the inlet 4 to the chamber 5 and preventing the entrance of combustion gases into the injector, the more so since the partial vacuum existing 95 in the chamber 5 causes the valve 14 to be pressed tightly against its seat.

If it is desired to utilize exhaust steam for the operation of the injector, which of course can be done only while the engine is running, the slide valve 15 is moved to the position in 100 which it shuts off the admission of steam to the conduit 10 and opens such admission to 110

the conduits 9 and 11. In this case live steam will pass through conduit 11 to the chamber 12, lifting the valve 13 which then raises the valve 14 off its seat thereby allowing exhaust steam to pass from the inlet 4 to the chamber 5 and the nozzle 2. Under these conditions, therefore, the injector will operate with boiler steam supplied to the live steam nozzle 1 and with exhaust steam supplied to the nozzle 2.

In the construction shown in Fig. 1 the valve operated by the hand lever 16 controls three outlets from the chamber in which it operates. Fig. 2 illustrates a construction in which the piston valve 18 actuated by the hand lever 16 controls only two outlets, indicated at 19 and 20 respectively. The outlet 19 leads to a chamber 21 communicating with the conduit 11. The outlet 20 leads to a chamber 22 communicating with the conduit 10, preferably through a constricted passage or duct. The conduit 9 communicates either with the chamber 21 or with the chamber 22, according to the position of a shifting valve 23 which is moved automatically by the pressure of the steam in that chamber, 21 or 22, which at that time, owing to the position of the controlling valve 18, is in communication with the live steam inlet 17. Fig. 2 shows the valve 23 in such a position that live steam will pass both to the conduit 9 and to the conduit 11. It will be understood that the parts not illustrated in Fig. 2 and connected with the conduits 9, 10 and 11 are to be of the same construction as in Fig. 1. When the piston valve 18 is moved to the position in which it closes communication between the inlet 17 and the outlet 19, it will admit steam to the outlet 20 and chamber 22, thus not only permitting live steam to pass to the conduit 10 but causing the valve 23 to shift so as to connect the conduit 9 with the chamber 22, and disconnect said conduit 9 from the chamber 21. From the description given in connection with Fig. 1 it will be understood readily that, in Fig. 2 as well, admission of steam to the conduits 9 and 10 will cause the injector to be operated with live steam alone, while admission of live steam to the conduits 9 and 11 will cause the injector to be operated with a combination of live steam and exhaust steam.

Fig. 3 shows an injector of the same general type as Fig. 1 but with an automatic device for shifting the steam connections of the conduits 9, 10 and 11. The shifting valve 24 has a small lower portion which, when resting on its lower seat 25 closes the communication from the live steam inlet 17 to the steam conduit 10. The upper end of this valve 24 is larger, and when lifted to engage the corresponding upper seat 26 closes the connection from the steam inlet 17 to the conduit 11. The steam conduit 9

is in permanent communication with the steam inlet 17. At 28 we have indicated a chamber which by means of a conduit 29 is in permanent communication with the slide valve chest of the engine. In this chamber 70 is arranged a valve 27 which when seated shuts off communication between the chamber 28 and the conduit 29. The valve 24 has an upward projection of such length that as said valve moves upward and before 75 it engages its upper seat 26, said projection will come in contact with the valve 27 and lift it from its seat. In other words the movement of the lower valve 24 is greater than the space or lost motion between those 80 portions of the two valves which come into engagement upon the upward movement of the lower valve 24. When the locomotive engine is running under steam and if live steam is admitted through the inlet 17, the 85 valve 27 will be seated because boiler pressure prevails in the chamber 28 in view of the fact that the conduit 29 connects said chamber with the slide valve chest. The shifting valve 24 will not be able to seat 90 upward, since the valve 27, held forcibly on its seat, will form a stop for the lower valve 24. The latter therefore will remain on its lower seat 25 so that the live steam will flow from the inlet 17 to the conduits 95 9 and 11. The steam flowing through the conduit 9 will be discharged through the nozzle 1, while the steam passing through the conduit 11 will lift the valve 13, opening the valve 14 as described above and allowing the exhaust steam to pass from the inlet 4 to the chamber 5 and the nozzle 2.

When the throttle of the locomotive is closed, so that there is no longer any exhaust steam, the pressure in the slide valve chest will fall to about atmospheric pressure. As a result, there will be practically no pressure in the chamber 28, and the boiler pressure prevailing in 17 will lift and press the valve 24 against its upper seat 26, since the valve 27 no longer will stop the upward movement of the valve 24. This will cause the pressure to drop in the conduit 11 and chamber 12, since the closing of the valve 24 against its upper seat disconnects the conduit 11 from the steam inlet 17. Both the valve 13 and the valve 14 will therefore drop to their lower positions, and the injector will operate exclusively with live steam supplied through the conduits 9 and 10, the steam flowing through the conduit 9 being of high pressure, while the pressure of the steam passing through the conduit 10 is somewhat lower, owing to the fact that the steam is throttled by the contraction shown at the upper end of the conduit 10.

In some cases it is desirable when starting the injector to admit only small amounts of steam but at a high velocity, into the injector nozzles in order to produce in the

water inlet 6 the suction or vacuum necessary for priming the injector, i. e. for starting the flow of water. This is the case particularly when the injector acts by suction, 5 in other words when it is located at a higher level than the surface of the water in the tender, or when the feed water is unusually warm. Fig. 4 is a partial view illustrating a construction suitable for this purpose, it 10 being understood that the injector nozzles and other parts connected with the steam conduits 9, 10 and 11 may be of the same character as shown in Fig. 3. The conduit 29 is connected with the slide valve chest or 15 some other part receiving steam only when the engine proper is in operation, and the conduit 31 is connected with the boiler. In this construction, we provide a controlling member 30, 32 which is arranged to open 20 first a passage from the steam inlet 31 to the conduit 9 and therefore to the nozzle 1, and thereupon a passage from said steam inlet 31 to either the conduit 10, or the conduit 11, according to the position of the 25 shifting valve 24, which is of the same character as described with reference to Fig. 3. It will be noted that the portion 32 of the controlling member is shaped as a piston sliding in an opening which connects the 30 conduit 9 with the chamber 17 in which the valve 24 is located. The portion of the controlling member which closes or opens the connection between the inlet 31 and the conduit 9 is constructed as a valve of the ordinary tapering shape. It will be evident from 35 Fig. 4 that when the controlling member is rotated by means of the hand wheel shown at its left hand end, said member will be moved toward the left, owing to the provision 40 of screw threads engaging corresponding threads in the stationary casing. The inlet 31 will thus be brought into connection with the conduit 9 and a small amount of high velocity steam will pass to the inner nozzle 45 1 thus starting the flow of water. As long as the cylindrical portion 32 of the controlling member remains within the opening leading from the conduit 9 to the chamber 17, no steam will pass through said opening, 50 since a practically steam tight fit is employed at this point. When however the controlling member has been moved to the left far enough to bring the right hand end of the cylindrical portion 32 entirely out of 55 the opening by which chamber 17 may communicate with the conduit 9, steam will pass from the inlet 31 both to the conduit 9 and to the chamber 17. The operation will then be the same as explained in connection with 60 Fig. 3, that is to say, as long as the engine proper is running, the valve 24 will be in its lower position, and the injector will be supplied both with live steam (through the conduit 9) and with exhaust steam (through the open valve 14), while when the engine

is standing still or when for any other reason there is practically no pressure in the chamber 28, the valve 24 will be lifted so that only live steam will be supplied to the injector (through the conduits 9 and 10). 70

In Figs. 5 and 6 we have illustrated two constructions which differ from those shown in Figs. 1 and 3 only in the following particular: The steam conduit 10 does not lead to a narrow annular chamber such as 3 in 75 Figs. 1 and 3, surrounding the inner nozzle 1 within the chamber 5, but such conduit 10 leads directly into the said chamber 5, preferably at the upper portion thereof. This arrangement is particularly of advantage in 80 cases where a restricted amount of space is available, so that the chamber 5 cannot be made of large external dimensions. By dispensing with those parts which in Figs. 1 and 3 surround the inner nozzle 1 to form the annular chamber 3 therewith, the effective cross section of the passage through which the exhaust steam may flow from the inlet 4 to the nozzle 2 is increased without 85 increasing the external dimensions of the chamber 5, and the throttling action exerted in Figs. 1 and 3 by the outer walls of the annular chamber 3 is avoided. It is true that in this case the kinetic energy of the 90 expanded live steam passing through the conduit 10 is not utilized, but this is not a serious objection if care is taken to avoid throttling the steam too much and thus effecting too great a reduction of its pressure. 95

Various modifications may be made without departing from the nature of our invention as set forth in the appended claims. For instance, piston valves, slide valves, or cocks may be substituted for the controlling member 30, 32 of Fig. 4, or any other device 100 that will accomplish the same function. Similarly the piston valves 15 and 18 of Figs. 1, 2 and 5, may be replaced with other devices accomplishing the same purpose, for instance slide valves, double valves, connected valves or the like. Where the annular chamber 3 is employed, as in Figs. 1 and 3, its outlet towards the nozzle 2 need not be an annular slit as illustrated but might consist of an annular series of openings 105 disposed around the nozzle 1. 110

We claim as our invention:

1. The combination with an exhaust steam injector having connected therewith, a conduit leading to the exhaust steam line of an engine, a second conduit for supplying auxiliary live steam to said injector, and a third conduit for supplying supplementary live steam to said injector, of a valve casing to which said second and third conduits are connected, means to supply live steam to said casing, a valve freely mounted in said casing, normally closing, and adapted to be moved by the pressure of the live steam in said casing to open said second conduit, fluid 115 120 125 130

pressure actuated means within said casing, and a pipe connecting said fluid pressure means with the main steam line of the engine, said fluid pressure means being constructed and arranged to contact with said freely mounted valve and prevent it from opening said second conduit when said pipe contains steam under pressure.

2. A combination as set forth in claim 1 in which a manually controlled valve is mounted within said casing for controlling the admission to said casing of steam from said live steam supply means.

3. A combination as set forth in claim 1 in which a manually controlled valve is mounted within said casing for controlling the admission of live steam thereto, said manually controlled valve being arranged when opened to permit the passage of said live steam to said third conduit and to said freely mounted valve.

4. The combination with an exhaust steam injector having connected therewith an exhaust steam conduit, an auxiliary live steam conduit and a supplementary live steam conduit, of a valve casing to which said supplementary and live steam conduits are connected, said valve casing being provided with a chamber having freely mounted therein an automatic valve adapted normally to close said auxiliary live steam conduit, and a manually operated valve mounted in said casing for controlling the admission of steam to said valve casing and chamber.

5. A combination as set forth in claim 4 in which said manually operated valve is so constructed and arranged that when it is opened live steam will be admitted first to said supplementary live steam conduit and then to said chamber.

6. The combination with an exhaust steam injector having connected therewith an exhaust steam conduit, an auxiliary live steam conduit and a supplementary live steam conduit, of a valve casing to which said auxiliary and supplementary live steam conduits are connected, and means for insuring the admission of live steam to said supplementary live steam conduit before the admission of live steam to said auxiliary live steam conduit.

7. The combination with an exhaust steam injector having connected therewith an exhaust steam conduit, an auxiliary live steam conduit and a supplementary live steam conduit, of a valve casing to which said auxiliary and supplementary live steam conduits are connected, means for connecting said casing with a source of live steam, an exhaust steam valve for controlling the admission of steam to said injector through said exhaust steam conduit, fluid pressure actuated means for operating said valve, a pipe connecting said valve casing and fluid pressure means, an automatic valve for admit-

ting live steam to said auxiliary live steam conduit or to said pipe and a manually operated valve for controlling the admission of live steam to said valve casing and supplemental live steam conduit, said manually operated valve being constructed and arranged to insure the admission of live steam to said supplemental live steam conduit before live steam is admitted to either said auxiliary conduit or said pipe.

8. In a control system for an exhaust steam injector, an exhaust steam conduit having a valve and fluid pressure actuated means for operating said valve, a supplementary live steam conduit, an auxiliary live steam conduit, an automatic valve for admitting steam to said fluid pressure means or to said auxiliary live steam conduit, and a manually operated valve for admitting live steam to said supplementary live steam conduit and then to said automatic valve, said manually operated valve being so constructed and arranged that the steam can not be admitted to said automatic valve before its admission to said supplementary live steam conduit.

9. An apparatus of the class described, comprising an inner nozzle, an outer nozzle, a chamber surrounding said inner nozzle and communicating with said outer nozzle, a pair of live steam conduits, one leading to said inner nozzle and the other discharging directly into said chamber, an exhaust steam inlet, a valve controlling a connection from said inlet to said chamber, another valve adapted to unseat and operate the first mentioned valve, a third live steam conduit leading to said second valve to operate it, and a controlling valve which in one position shuts off live steam from said third conduit, while in another position said controlling valve shuts off steam from the conduit leading to said chamber.

10. An apparatus of the class described, comprising an inner nozzle, an outer nozzle, a chamber in which said inner nozzle is located, live steam conduits leading respectively to said chamber and to the inner nozzle, an exhaust steam inlet, a live steam inlet in permanent communication with one of said conduits, an automatic controlling valve which in one position shuts off connection from said steam inlet to the other conduit, and in another position opens such connection, an exhaust steam inlet, a valve controlling a connection from said exhaust steam inlet to said chamber, an actuating valve adapted to unseat and operate said exhaust-controlling valve, a conduit for supplying steam from the live steam inlet to such actuating valve when the controlling valve is in such position as to close the inlet to the conduit leading to said chamber, another chamber having a connection for supplying high pressure steam thereto when the engine

is in operation, and a valve controlling the connection of the last mentioned chamber with the conduit leading to the actuating valve, the latter forming a stop to normally prevent the seating of the controlling valve on that seat which is related to the conduit leading to the actuating valve.

11. An apparatus of the class described, comprising an inner nozzle, an outer nozzle, a chamber in which said inner nozzle is located, live steam conduits leading respectively to said chamber and to the inner nozzle, an exhaust steam inlet, a live steam inlet in permanent communication with one of said conduits, an automatic controlling valve having at its respective ends, seating surfaces of different diameters, the smaller surface being adapted to control the connection of the said steam inlet with the other conduit, an exhaust steam inlet, a valve controlling a connection from said exhaust steam inlet to said chamber, an actuating valve adapted to unseat and operate said exhaust-controlling valve, a conduit for supplying steam from the live steam inlet to such actuating valve, the connection of said conduit with the live steam inlet being controlled by the portion of the controlling valve having the larger seating surface, an-

other chamber having a connection for supplying high pressure steam thereto when the engine is in operation, and a valve controlling the connection of the last mentioned chamber with the conduit leading to the actuating valve, the latter forming a stop to normally prevent the seating of the controlling valve on that seat which is related to the conduit leading to the actuating valve.

12. An apparatus according to claim 10, in which an additional controlling member operates to connect the live steam inlet first only with the conduit leading to the inner nozzle and subsequently also to the automatic controlling valve.

13. An apparatus according to claim 10, in which there is provided an additional controlling member composed of a valve controlling the connection of the live steam inlet with the conduit leading to the inner nozzle, and a sliding piston fitted to an opening which connects said conduit with the chamber containing the automatic controlling valve, when said piston is clear of said opening.

In testimony whereof we have hereunto set our hands.

LOUIS FRIEDMANN.
HANS DEUTSCH.
